L. D. ARMSTRONG

GRID FOR COTTON PICKER MACHINES

Filed July 18, 1923

UNITED STATES PATENT OFFICE.

LINUS D. ARMSTRONG, OF PROVIDENCE, RHODE ISLAND.

GRID FOR COTTON-PICKER MACHINES.

Application filed July 18, 1923. Serial No. 652,354.

To all whom it may concern:

Be it known that I, LINUS D. ARMSTRONG, a citizen of the United States, residing at Providence, in the county of Providence and 5 State of Rhode Island, have invented certain new and useful Improvements in Grids for Cotton-Picker Machines, of which the following is a specification.

This invention relates to improvements in 10 the construction of grids for cotton pickers; and the object of this invention is to provide a grid for the purpose of cleaning the cotton which passes through the picker, the grid being provided with side plates and a notched 15 slide plate mounted to be adjusted on one of said side plates; a series of grid bars being engaged at one end by the slide plate and pivotally mounted to rock in said side plates by movement of said slide plate, and said 20 slide plate being movable by means of an operating lever which is pivoted in the side plate, whereby a movement of the lever adjusts the grid bars through a movement of the slide plate, and means being provided 25 for locking the slide plate in adjusted position.

With these and other objects in view, the invention consists of certain novel features of construction, as will be more fully 30 described, and particularly pointed out in the appended claims.

In the accompanying drawings:

Figure 1 is a side elevation showing one 35 of the side plates in which the grid bars are pivotally mounted; also showing the operating lever and the slide plate dotted in position on the side plate.

Figure 2 is a perspective view of the slide 40 plate detached from the side plates; and showing its operating lever as connected thereto.

Figure 3 is an end view partly in section 45 showing a portion of one of the grid bars pivotally mounted in the side plate; also showing the slide plate as engaged by its operating handle.

Figure 4 is an enlarged perspective view of a portion of one of the grid bars.

Figure 5 is a side elevation of a portion 50 of the side plate showing the notches therein, in which the grid bars are rotatably mounted on their trunnions.

It is found in the practical construction 55 and operation of grids for cotton pickers, of advantage to provide and pivotally mount a series of grid bars whereby their operating

angle may be simultaneously adjusted by rocking the bars upon their pivotal axis so as to act upon different qualities of material which are passed through the picker, and to 60 so construct the movable parts of the grid that they will not be clogged by foreign matter removed from the cotton and to also provide a lever having a handle of such a length that it may be readily engaged and 65 moved to operate the grid bars to adjust them to the required position also to provide means whereby these movable members may be securely locked in any adjusted position; and the following is a detailed description 70 of one means by which these advantageous results may be accomplished:

With reference to the drawings, 10 designates the side plates which are secured by means of bolts 11 to the inner faces of the 75 opposite side frames of the cotton picking machine (not shown). These plates are preferably formed on the arc of a circle and the upper edge thereof is provided with a series of recesses 12 over the top of which 80 is secured a plate 13. These side plates are also provided with an arc shaped slot 14 into which the laterally extending flange 15 of the slide plate 16 extends and slides. This flange 15 is preferably notched on its edge 85 as at 17 for the purpose of engaging the lower edge of the grid bars 18. Each of these grid bars 18 is provided with end trunnions 30 which are mounted to rock in the recesses 12 of the opposite side plates 10. The lower 90 edge of this slide plate is provided with a deep notch 19 into which the upper end 20 of the operating lever 21 fits.

This operating lever is pivotally mounted 95 at 22 to the extension arm 23 on the side plate 10, whereby the free end of the lever when grasped by the hand of the operator is caused to exert a greatly increased force upon the slide plate to move it with its grid bars into the desired adjusted position.

In this lever, I have mounted a pin 24 which extends through a slot 25 in the side plate and is threaded to receive a thumb nut 26, whereby this lever may be bound in any adjusted position to lock the 105 slide plate and the grid bars after having received the required adjustment.

In addition to the locking nut 26 on the lever 21, I have also provided a locking and stroke-limiting screw 27 in the slide 110 plate extending through a slot in the side plate, in a position adjacent the point of

engagement of the slide plate with the grid bars, whereby by setting up this latter screw the slide plate is also bound in adjusted position to provide a double lock and so positively prevent any movement of the slide plate after having been adjusted.

By my improved construction of operating lever for the slide plate, the slot 19 formed in this plate is open at its lower edge thereby preventing any accumulation of foreign matter therein which might serve to bind and prevent the free adjusting movement of the operating lever.

My improved construction of grid for cotton pickers is extremely simple and inexpensive to construct, is easy to apply and is very effective in its operation, and by its use the grid bars may be nicely adjusted and firmly locked and secured in such adjusted position.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A grid for a cotton picker, having side plates, a notched slide plate mounted on one side plate, a series of grid bars engaging

the notches in said slide plate and mounted to be rocked in said side plates by the movement of said slide plate, a slide plate operating lever pivoted in said side plate and having one end in engagement with said slide plate, means adjacent the application of strain tending to cause a relative movement of said plates for locking said slide plate in adjusted position, and means for locking said lever in adjusted position.

2. In a grid for cotton pickers, a curved side plate having an arcuate slot therein, a plate slidably mounted on said side plate having a portion with a notched edge laterally extending at right angles thereto through said slot, a series of grid bars the ends of which are engaged by the notches of said slide plate and pivotally mounted to be rocked in said side plates by the movement of said slide plate, said slide plate having a deep notch in its lower edge, a slide plate operating lever pivoted in said side plate with its upper end extending into said notch whereby a movement of said lever moves said slide plate to adjust said bars to the desired angle, and means for locking the slide plate in adjusted position.

In testimony whereof I affix my signature.

LINUS D. ARMSTRONG.
